UNITED STATES PATENT OFFICE.

FRANK FÖLDI, OF CLEVELAND, OHIO.

LIFE-SAVING NET.

1,099,352.

Specification of Letters Patent.

Patented June 9, 1914.

Application filed March 9, 1914. Serial No. 823,486.

To all whom it may concern:

Be it known that I, FRANK FÖLDI, a subject of the King of Hungary, residing at Cleveland, in the county of Cuyahoga and State of Ohio, have invented certain new and useful Improvements in Life-Saving Nets, of which the following is a specification.

This invention relates to certain new and useful improvements in life-saving nets adapted for use as a body-catching device.

The primary object of this invention is to provide a body-catching net resiliently suspended for cushioning the fall of a body when striking therein from a considerable height, such as would be incident from the jumping of a person from an upper story of a burning building.

A further object of the device is to provide a mechanical means for suspending the life net in lieu of a holding thereof by the firemen and which suspending device moreover shall be resilient and yielding upon the dropping of a body thereinto.

A still further object is to provide a net holder which may be moved upon a wheeled base to the desired position for use and which will sustain the net suspended and resiliently allow a downward movement thereof counterbalanced by weights.

With these general objects in view and others that will appear as the nature of the invention is better understood, the same consists in the novel combination and arrangement of parts hereinafter fully described, illustrated in the accompanying drawings, and pointed out in the appended claims.

In the drawings forming a part of this application and in which like designating characters refer to corresponding parts throughout the several views:—Figure 1 is a perspective view of the device showing the net positioned for use. Fig. 2 is a top plan view of one of the post supporting means. Fig. 3 is a perspective view of one of the posts detached, and, Fig. 4 is a perspective view of one of the net-carrying sliding blocks detached.

Referring more in detail to the drawings, the platform 10 is illustrated as mounted upon wheels or rollers 11 for readily positioning the device at the desired point with respect to a burning building and so as to allow the occupants to jump within the net 11 carried above the platform.

At each corner of the platform as now

illustrated and at other points along the edges thereof if desired, are positioned supporting posts 12 having their outer faces provided with vertical slots 13 adapted to slidably-receive weight members 14 to which are attached cords 15 running over sheaves or rollers 16 upon the tops of the posts, the cords being then secured to the blocks 17. Spring boards 26 are positioned adjacent the inner opposite faces of the posts 12 and are held normally downwardly convergent by means of springs 27 connecting said posts and boards, it being noted that the springs are of greater length adjacent the lower ends of the posts than those positioned thereabove. Said blocks 17 have a spacing rod 28 rigidly secured therebetween while the net 11 which is secured to the blocks is also secured to or around the opposite end rods 28. A separate one of said blocks 17 is provided as illustrated at each corner of the net 11 and has a dove-tailed groove 18 in its outer face adapted to receive and slide upon the tenon 19 upon the inwardly-positioned inclined face 20 of the spring-board 26. The block 17 is provided at the rear face of the groove 18 with a heavy coil spring 21 adapted to press against the outer face of the tenon 19 when the block is slidably-positioned thereon.

With this described construction, the complete operation thereof will be apparent, the net being suspended from the four corner blocks 17, a heavy body dropping within the net gradually lowers the same simultaneously with a raising of the counter-weights 14 while the springs 21 of the blocks resiliently allow the latter to slide downwardly upon the respective spring-board tenon and whereby a cushioning effect is produced for the alighting and thus preventing harm or injury to the person escaping from the burning building. The springs 27 are compressed upon a downward movement of the net by reason of the fixed distance between the blocks which slide upon the tenons 19 as insured by the spacing rods 28 and by which it will be seen that the downward movement of the net is cushioned by such arrangement.

While I have herein shown and described the preferred embodiment of my invention, I do not wish to limit myself thereto, as various forms and modifications may be had which will fall within the spirit and scope of the invention.

Having thus fully described my invention, what I claim as new is:—

1. A device of the class described comprising a movable platform, grooved posts upon 5 said platform, upwardly-diverging boards resiliently mounted upon said posts, blocks slidably positioned upon said boards rigid spacing means between opposite ones of said blocks, a net secured between said blocks, 10 weights within the grooves of said posts, and connecting means between said weights and blocks.

2. A life-saving apparatus comprising a platform, a post at each corner of the platform having a longitudinal groove in its outer face, an inclined board resiliently mounted upon the inner opposite faces of 15 said posts, longitudinal tenons upon the inner face of each board, rollers upon the tops 20 of said posts and boards, a grooved block slidably positioned upon the tenon of each board, a rod rigidly secured between the opposite ones of said blocks, a life net secured between said blocks, counter-weights 25 within the grooves of said posts, and suspending devices connecting said counter-weights and blocks and running over said rollers.

3. A device of the class described comprising 30 a movable platform, a vertical post positioned at each corner of the platform and having a longitudinal groove in its outer face, downwardly convergent boards positioned inwardly of said posts, different

length springs between said boards and adjacent posts, a tenon mounted upon the inner face of each board, a block having a tenon groove therein adapted for slidably mounting upon said tenon, a spring member within the groove of said block engageable 40 with the outer face of the tenon, a life-net secured between said blocks rigid spacing means between opposite ones of said blocks, counter-weights within the grooves of said posts, and suspending cords between said 45 weights and blocks.

4. A device of the class described comprising a platform, a post at each corner of the platform having a slotted outer face, inclined plates resiliently secured to the inner 50 faces of each of said posts, and having tenoned inner faces, blocks having tenon grooves adapted for slidably-engaging said tenons, spacing rods rigidly secured between opposite ones of said blocks, springs within 55 the slots of said blocks resiliently engaging the outer faces of said tenons in the downward movement of the blocks, a net secured to said blocks and spacing rods, and counter-weight members within the outer grooves of 60 said posts and connected to said blocks.

In testimony whereof I affix my signature in presence of two witnesses.

FRANK FÖLDI.
